UNITED STATES PATENT OFFICE.

JULIUS W. FISCHER, OF SAN FRANCISCO, CALIFORNIA, ASSIGNOR OF ONE-HALF TO
LOUIS WALLERSTEIN, OF SAN FRANCISCO, CALIFORNIA.

JAR OPENER.

Application filed April 27, 1925. Serial No. 26,056.

This invention relates to jar openers of the type having a handle portion and a band thereon adapted to surround a jar cover and to be drawn into tight engagement therewith. I am aware that many jar openers of this type have been devised. All such openers, however, as far as I am aware, do not grip the jar cover tightly except when the band is held in tight engagement by a manual force exerted on the handle portion of the opener. It is the primary object of my invention to provide a jar opener embodying means for drawing the band into tight engagement about a jar cover and securely holding the same in such position.

It is a further object of my invention to provide a jar opener embodying means for drawing the band into tight engagement about a jar cover and other means co-operating therewith for holding the band so engaged and simultaneously therewith further tightening the band.

In the accompanying drawing I have illustrated one specific embodiment of my invention, but it will be understood that the invention can be otherwise embodied and that the drawing is not to be construed as defining or limiting the scope of the invention, the claims appended to this specification being relied upon for that purpose.

Referring to the figures of the drawing, Fig. 1 is a side elevation of my improved jar opener, showing the handle portion thereof in section and the band thereof in place on a jar cover;

Fig. 2 is a plan view thereof, partially in section.

Referring more specifically to the drawing by reference characters, 1 indicates a piece of brass tubing, rectangular in cross-section, which forms the main handle portion of my improved jar opener. Co-operating therewith is a steel band 2 adapted to surround a jar cover 3. The ends of this band are secured to a block 4 slidably mounted in the handle 1, the band extending to the opposite sides of a bridge piece 5 secured in the end of the handle by screws 6. A toothed rack 7 is secured to the block 4 as illustrated.

A pinion 8 on a shaft 9 carried by the plates 10 secured to the sides of the handle is in mesh with the rack 7, an operating knob 11 being provided on the shaft. A pinion-engaging slide 12 is connected by a screw 13 to a stud 14 mounted in the handle 1. Rota-

tion of the screw is adapted to move the slide into and out of engagement with the pinion.

It is believed that the operation and advantages of my invention will be clear without further description herein. The resiliency of the band 2 is such that it normally spreads out to its full opening, thereby drawing the block 4 to the extreme left end of the handle 1. In operation the band is placed over a cover to be removed and the shaft 9 rotated in the direction of the arrow to draw the block inwardly and close the band onto the cover. When the band is in tight engagement with the cover the screw 13 is rotated to engage the plate 12 with the pinion. As seen in Fig. 1, the plate engages a pinion tooth above the pinion axis in a manner to not only hold the pinion against backward rotation but to further rotate the same in the direction of the arrow. Thus this rotation of the screw not only holds the band tightly engaged with the cover, but serves to further tighten the same into a binding and gripping engagement therewith. It will be noted that the moving and tightening of the band about the jar cover and the holding of the same are all accomplished by the movement of the several parts of the jar opener relative to the handle. In removing the cover the bridge piece 5 co-operates with the band as illustrated in Fig. 2.

The construction of my invention is simple and cheap to manufacture and the operation thereof is most efficient. The resiliency of the band 2 normally holds the device in the wide open position for engaging the largest size covers. Covers of any size from the largest to the smallest can be engaged and removed with like efficiency. Furthermore, the operation thereof requires no hard hand gripping of the handle portion, as do most jar openers, and when once in position on a cover, the opener is securely held in such position until removed by releasing the screw 13.

Having thus described my invention, what I claim as new and desire to secure by Letters Patent is:—

1. A jar opener comprising the combination of a handle, a member movably carried thereby, a band connected to the member and adapted to surround a jar cover, means on the handle for moving the member to draw

the band tightly about the cover, and means for holding the band so drawn and thereafter further tightening the band and simultaneously therewith holding the same 5 against loosening, the band tightening and holding means being movable relative to the handle in the said band tightening and holding operations.

2. A jar opener comprising the combination of a handle portion, a band connected thereto and adapted to surround a jar cover, rotary means for drawing the band tightly about the cover, means operative on the rotary means to hold the same in the band-tightened position, and cooperating means 10 to further tighten the band relative to the handle.

3. A jar opener comprising the combination of a handle portion, a band connected thereto and adapted to surround a jar cover, 20 rotary means for drawing the band tightly about the cover, and means operative on the rotary means to further tighten the band and hold the same in its tightened position.

4. A jar opener comprising the combination of a handle, a toothed rack therein, a band connected to the rack and adapted to surround a jar cover, a pinion engaging the rack and adapted upon rotation in one direction to tighten the band on the cover, and 25 means for engaging the pinion to rotate the same in the said band tightening direction.

JULIUS W. FISCHER.
